CLAIM

The ornamental design for a clip for an eye glass lens occluder, as shown and described.

DESCRIPTION

FIG. 1 is a side elevational view of a clip for an eye glass lens occluder showing my new design, the opposite side being a mirror image;

FIG. 2 is a rear elevational view thereof;

FIG. 3 is a bottom plan view thereof;

FIG. 4 is a top plan view thereof; and

FIG. 5 is a front elevational view thereof.
